UNITED STATES PATENT OFFICE.

JAMES E. CHILDS, OF SPOKANE, WASHINGTON.

HARP.

SPECIFICATION forming part of Letters Patent No. 739,647, dated September 22, 1903.

Application filed January 28, 1903. Serial No. 140,863. (No model.)

To all whom it may concern:

Be it known that I, JAMES E. CHILDS, a citizen of the United States, residing at Spokane, in the county of Spokane and State of Washington, have invented new and useful Improvements in Harps, of which the following is a specification.

My invention relates to improvements in harps, and has for one of its objects to provide a harp the strings of which are disposed in a hollow horn-shaped body calculated to increase the power of the tones and are adapted to be picked at a point adjacent to where their upper ends are fastened, this latter in order that when a string breaks only a small portion of the string need be lost and the remainder and major portion thereof may be drawn up through the bridge and again fastened.

Another object is to provide a harp embodying simple, inexpensive, and light devices through the medium of which a harpist may readily sharp the strings, when desired, with his thumbs.

With the foregoing in mind the invention will be fully understood from the following description and claims when taken in conjunction with the accompanying drawings, in which—

Figure 1 is a side elevation of a harp constituting one embodiment of my invention; Fig. 2, a front elevation of the same; Fig. 3, a transverse section taken in the plane indicated by the broken line 3 3 of Fig. 1; Fig.

4, an enlarged vertical section taken in the plane indicated by the broken line 4 4 of Fig. 1; Fig. 5, a detail side elevation of the upper portion of the harp, illustrating the relative arrangement of the strings and the thumb devices for sharping the strings; and Fig. 6, an enlarged perspective view of one of the said thumb devices removed.

Similar letters of reference designate corresponding parts in all of the several views of the drawings, referring to which—

A is the hollow horn-like body of my improved harp, which is made of wood or other suitable material and is by preference shaped to resemble a whale, as shown. In the preferred embodiment of my invention the back wall *a*, side walls *b*, foot or base *c*, and head *d* of the said body are each formed of one

piece, while the front wall *e* is suitably connected to the side walls, head, and foot or base. The side walls *b* are provided with exterior strips or bridges *f* and have their upper ends disposed about the distance illustrated below the head *d*, this latter in order to provide a space *g*, in which the strings may be conveniently picked.

B B are the strings. I have shown but eighteen strings, nine at each side of the head *d*; but I desire it understood that in practice I prefer to employ fourteen strings in the treble row at the right-hand side of the head *d* and fourteen strings in the bass row at the opposite side of the head *d*. I also prefer to tune the strings in the treble or right-hand row two octaves above the strings in the bass or left-hand row and to arrange the strings in the treble row in transverse alinement with the corresponding strings in the bass row, and so that the lowest string in the treble row will be middle C and the lowest string in the bass row will be C two octaves lower, and so on up the scale. From this it follows that the harp may be played in the same manner as an ordinary harp. The lower portions of the strings B are wrapped around or otherwise secured to buttons *h*, disposed at the outer sides of the strips or bridges *f*, and from said buttons the strings are passed through the bridges and the side walls *b* of the body and up to the head *d*, where they are passed over metallic pins *i* and suitably secured to tuning-keys *j*.

C is a hook, preferably of metal, connected to the upper portion of the body at the back thereof and adapted when the harp is to be played to be placed over the right shoulder of the harpist, so as to cause the harp to stand at an angle of about forty-five degrees and in a convenient position for the harpist to reach the treble strings with his right hand and the bass strings with his left hand, and D D are the thumb devices, of metal or other suitable material, for sharping the strings when desired. These devices in the preferred embodiment of my invention respectively comprise a rock-shaft *k*, disposed transversely in the head *d* of the body A and having depending lugs *l*, one of which is arranged to engage a treble string and the other the corresponding bass string, and a depend-

ing thumb-piece *m* at one end of the rock-shaft. The lugs *l* and thumb-pieces *m* are arranged as stated with relation to the rock-shafts *k* in order to assure the lugs *l* normally hanging clear of the strings. The devices *D* are preferably arranged in the head *d*, as best shown in Figs. 4 and 5—i. e., the device for sharpening the C strings is arranged with its thumb-piece at one side of the head *d* and the device for sharpening the D strings is arranged with its thumb-piece at the opposite side of the head *d*, and so on. From this it follows that the harpist is enabled to use the thumb of one hand to sharp some of the strings and the thumb of his other hand to sharp the alternate strings, and it will also be observed that when a thumb-piece is pressed both the treble string and the corresponding bass string which it is arranged to engage will be sharped.

It will be appreciated from the foregoing that in virtue of the strings being disposed in the hollow horn-shaped body the power of the tones produced by picking the strings is greatly increased, and it will also be appreciated that the picking of the strings in the space *g*, adjacent to the keys *j*, is advantageous, since when a string is worn in two the major portion of the string below the picking-point may be drawn up and fastened to its complementary key. It will be further gathered from the foregoing that my improved harp is advantageous, because the strings within the body *A* are protected against dampness and injury and also because the devices employed for sharpening the strings are very light and inexpensive and add but little to the weight and cost of the harp.

I have entered into a detailed description of the construction and relative arrangement of the parts embraced in the present and preferred embodiment of my invention in order to impart a full, clear, and exact understanding of the same. I do not desire, however, to be understood as confining myself to such specific construction and arrangement of parts, as such changes or modifications may be made in practice as fairly fall within the scope of my invention as claimed.

Having described my invention, what I claim, and desire to secure by Letters Patent, is—

1. A harp comprising a hollow, horn-shaped body having a head at one end, and openings in its sides, adjacent to said end, forming a picking-space, and strings arranged in the

hollow body, and connected at one end to the main portion of the body, and at their opposite ends to the head thereof.

2. A harp comprising a hollow, horn-shaped body having a head at one end, and openings in its sides, adjacent to said end, forming a picking-space, bass and treble strings arranged in the body at opposite sides of the head, and connected at one end to the main portion of the body, and at their opposite ends to the head thereof, and sharpening devices mounted in the head, and each having a portion to engage a treble string, and a portion to engage the bass string corresponding to said treble string.

3. In a harp, the combination of a body, bass and treble strings secured in the body, and arranged so that each treble string is opposite a corresponding bass string, and a sharpening device complementary to each bass string and the corresponding treble string; the said devices being mounted in the body, and each having means for simultaneously engaging a treble string and a corresponding bass string.

4. A harp comprising a hollow, horn-shaped body having its back and front walls extended beyond its side walls at one end, and a head interposed between the extended portions of the back and front walls, and treble and bass strings arranged at opposite sides of the head and in the body, and interposed between and connected to said head and the main portion of the body.

5. In a harp, the combination of a hollow, horn-shaped body open at one end and having a head at such end, base and treble strings arranged in the body at opposite sides of the head and interposed between and connected to said head and the main body portion, and a sharpening device complementary to each bass string and the corresponding treble string; the said devices respectively comprising a rock-shaft journaled in the head of the body, and extending transversely thereof, lugs depending from the rock-shaft and arranged to engage the bass and treble strings, and a thumb-piece depending from one end of the rock-shaft.

In testimony whereof I have hereunto set my hand in presence of two subscribing witnesses.

JAMES E. CHILDS.
